(57) **CLAIM**

The ornamental design for a faucet handle, as shown and described.

DESCRIPTION

FIG. 1 is a perspective view of a faucet handle showing my new design;

FIG. 2 is a first end view thereof;

FIG. 3 is a top plan view thereof;

FIG. 4 is a second end view thereof;

FIG. 5 is a first side view thereof, the opposite side being a mirror image of the side shown; and,

FIG. 6 is a bottom view thereof.

The broken-line disclosure in the view represents a portion of the faucet handle in which the claimed design is embodied, but which forms no part of the claimed design.
